UNITED STATES PATENT OFFICE.

GEORGE A. MACBETH AND HENRY A. SCHNELBACH, OF PITTSBURG, PENNSYLVANIA, ASSIGNORS TO MACBETH-EVANS GLASS COMPANY, OF PITTSBURG, PENNSYLVANIA, A CORPORATION OF PENNSYLVANIA.

LAMP-GLOBE.

No. 845,962.

Specification of Letters Patent.

Patented March 5, 1907.

Application filed August 23, 1906. Serial No. 331,759.

To all whom it may concern:

Be it known that we, GEORGE A. MACBETH and HENRY A. SCHNELBACH, citizens of the United States, residing at Pittsburg, in the State of Pennsylvania, have jointly invented certain new and useful Improvements in Lamp-Globes, of which the following is a specification.

Our invention relates especially to the protective globes used upon inverted gas-lamps and the like; and its primary objects are to provide proper ventilation for the burner, while at the same time closing the bottom of the globe to prevent dirt or carbon and fragments of the mantle from dropping through it; to provide an easily-removable closure for the bottom of an open-mouthed globe without destroying the symmetry of the globe; to provide better distribution of the air for perfect combustion and to protect the mantle, and to otherwise improve the efficiency of lamp-globes.

In the accompanying drawing, Figure 1 is a central vertical section of a lamp-globe and side elevation of the ventilating-valve applied therein. Fig. 2 is an under plan view of this valve or ventilator, and Fig. 3 is a central vertical section of the same. Figs. 4 and 5 illustrate, respectively, in plan and in section on the line 5 in Fig. 4 a modified form of the device. Fig. 6 shows another form in which the valve is a lens.

In the use of inverted gas-lights it is necessary, of course, to provide in the protecting-globe sufficient ventilation, and it is highly desirable to provide such ventilation from below and also to have the air completely surround the flame. Globes with open bottoms have been found to be dangerous, because pieces of the mantle may drop through and cause fire, and in attempting to overcome this difficulty globes have been made with solid closed bottoms, while for ventilation a series of holes are formed in the side of the globe near the bottom. This plan, however, is highly objectionable, because the air is concentrated as a draft on fixed spots on the mantle, and thus causes its rapid deterioration. In order to overcome these and other difficulties and also to enable the easy cleaning of the globe and inspection or removal of parts or any collected dirt, we provide, the

construction shown in the drawings, in which the lamp 7 is placed inside of a globe 8, which practically surrounds it, and is symmetrical in outline. The globe is open at the bottom for ventilation and for easy cleaning or inspection of the burner. The globe has no perforations; but the opening is closed by a ventilating-valve 9, which may be of any form desired, but preferably cup-shaped and completing the contour of the globe, and it is made with a flange 10, holding it within the opening in the globe. In Fig. 1 it is practically a hollow cone of glass in form that may easily be molded, and is provided with ribs 11, extending along the flange 10 and down the vertical sides 12, which register with the opening in the globe, so that the valve may be self-centering and fit neatly in place and yet allow ample open spaces 13 for ingress of air. The flaring flange 10 of the valve 9 extends outward over the air-passages 13, so that no particles from the lamp or other trash can drop through the globe. This shape of the valve and the flange causes a current of air directed along the open surface of the globe and completely surrounding the flame by diffused draft, thus protecting the glass and improving the oxidation and the even wear of the mantle.

In Figs. 4 and 5 is shown a modified form, having a series of scallops, and these will of course be made to correspond with the design of the globe. Usually the globe will be made opaque on top and the valve transparent. In some cases, as in library-lamps, it may be desirable to concentrate the light in a vertical direction, and in such case the globe is made opaque on top and with shoulders 14 to reflect light downward, as shown in Fig. 6, and the valve 15 is made in the form of a lens, with projections 16 to space it from the opening and hold it in the globe. The globe by these means is made complete in contour, and the bottom is closed against the falling out of any particles from the burner, and yet there is provided ample and well-distributed ventilation for the burner. The valve may be readily taken out in order to inspect the burner or to more efficiently clean the globe. Other advantages will readily occur to those familiar with the art.

Having thus described our invention and

22
illustrated its use, what we claim as new, and desire to secure by Letters Patent, is the following:

1. The combination with a lamp-globe having an opening in the bottom, of a combined shield and ventilator comprising a cone with a flange extending into the globe and its point extending through the opening, said shield being provided with inclined ribs adapted to engage the globe and space the shield therefrom.

2. The combination of a glass lamp-globe having a plain opening in its bottom, a transparent shield and ventilating-disk placed in the opening to catch detritus from the lamp, said disk continuing the outline of the globe and having a flaring upper end substantially parallel with the surface of the globe and having integral ribs thereon to space it from the globe, substantially as described.

3. The combination with a reflecting lamp-

globe having an open bottom, of a transparent lens-valve placed in and covering the bottom opening of the globe and having means for allowing ventilation, substantially as described.

4. The combination with a lamp-globe having an opening in the bottom, of a lens adapted to hang through said opening, and provided with means on the lens to center and support it on but space it from the globe, whereby ventilating-openings are provided around the circumference of said lens, substantially as described.

In testimony whereof we have hereunto signed our names in the presence of the subscribed witnesses.

GEO. A. MACBETH.

HENRY A. SCHNELBACH.
